UNITED STATES PATENT OFFICE.

WARREN R. MINNICK, OF READING, PENNSYLVANIA.

DISPLAY PANEL.

1,423,003.

Specification of Letters Patent.

Patented July 18, 1922.

Application filed January 12, 1921. Serial No. 436,686.

To all whom it may concern:

Be it known that I, WARREN R. MINNICK, a citizen of the United States, residing at Reading, in the county of Berks and State of Pennsylvania, have invented certain new and useful Improvements in Display Panels, of which the following is a specification.

My invention relates particularly to display panels or cards which are commonly used for advertising purposes; and it consists in providing improved supporting means therefor as fully described in connection with the accompanying drawing, the novel features being clearly defined in the claim.

Fig. 1 shows a rear elevation of a portion of a display panel having my supporting device in normal inoperative position thereon; supporting positions to which the portions thereof are movable being indicated in dotted lines.

Fig. 2 is cross-sectional view on the line 2—2 of Fig. 1; the several positions to which respective portions of the supporting device are movable being indicated.

Fig. 3 is a similar view to Fig. 1 but showing the supporting-leg portion of the device swung into the suspending position as indicated by dotted lines in Fig. 1.

The construction specifically shown embodies my complete invention in preferred form, and the cross-sectional view thereof exaggerates the thicknesses of the sheet material employed so as to clearly reveal the construction.

The display panel comprises a sheet metal back 5 and an ornamental facing 6 of embossed celluloid or the like formed up as usual with folded marginal portions 7. In the preferred construction shown I employ in addition a secondary backing sheet 8, of stiff paper or the like, which is also folded in at the marginal portions 7 and which is utilized, as shown, in pivotally securing the supporting-strip attachment 10.

This supporting attachment 10 is a narrow strip of thin metal or like flexible material, secured to the back of the panel at a point 11 intermediate of its length so as to form

oppositely extending portions 12 and 13 of 50 different lengths from said point of attachment. This fastened strip is normally held close to the back of the panel, preferably with the lower end of its longer portion 12 engaged in a marginal pocket 14 of the panel 55 as indicated; but for service, each portion is independently bendable into a panel-supporting position as may be required for convenient display. Thus the apertured shorter portion 13 may be bent back to the dotted-line position 13^a so as to serve as a suspension arm for the panel; while the longer portion 12 may be bent back to the dotted-line position 12^a so as to serve as a supporting leg on a table or the like.

As shown the supporting attachment 10 is provided with a pivotal connection to the panel which permits of its moving upon the connecting point 11 so as to enable its longer portion 12 to be used not only as a 70 supporting leg as indicated at 12^a, but also when desired, as a long suspension arm in the manner indicated in Fig. 3 and at 12^b Fig. 2. This pivotal connection is preferably made, as shown, by spot-welding the 75 supporting strip 10 to a rotatable plate 15 interposed between the metal back 5 and the secondary backing sheet 8; the latter being apertured to permit welding contact of the supporting strip 10 and the retaining plate 80 15. If this swinging movement of the strip 10 is not desired the connection 11 may obviously be made rigid instead of pivotal, and the construction particularly set forth may be otherwise modified within the invention 85 as defined in the claim.

What I claim is:

A display panel comprising a metallic backing sheet and a secondary backing sheet marginally flanged together, a metal disc 90 interposed between said backing sheets, an aperture in said secondary backing sheet exposing part of said disc, and a metallic supporting strip secured to said disc by a spot weld through said backing aperture.

In testimony whereof I affix my signature.

WARREN R. MINNICK.
